TAPPING AND REFILL-CONTROLLING
DEVICE FOR LIQUID CONTAINERS

Christoph Karageorgieff, Vienna, Austria

Application December 26, 1935, Serial No. 56,278
In Austria March 20, 1935

10 Claims. (Cl. 277—66)

This invention relates to tapping and refill-controlling devices for containers such as barrels and the like.

In my co-pending U. S. application, Serial Number 12,278, filed March 21, 1935, there is described a tapping and refill-controlling device the filling ports or passages of which are adapted to be closed off under lock control, and the tapping ports or passages of which are so governed by automatically acting closing means that tapping is possible at all times while re-filling is only possible after unlocking the means controlling the filling ports or passages, and then not through the tapping ports or passages.

The present invention relates to devices of this nature, and has for its object to increase the certainty with which refilling through the tapping outlet and passages is prevented.

With this object in view there are employed in accordance with the present invention, as the automatically acting closing means governing the tapping ports or passages, slide valves (straight movement slide valves, rotary slide valves, and the like) which are simple in operation, and, in consequence of their construction, less liable to suffer under heavy duty, than other kinds of valves. Now it would be possible for the attempt to be made, by the introduction of a piece of wire or other implement, to check the functioning of the automatically acting slide valves, and thus, in certain particular circumstances, to make it possible for refilling to be effected through the tapping ports or passages. This possibility, however, is eliminated by the means to be described in the present specification and intended for use in combination with the remaining features of the device described in my above-mentioned co-pending application. These means consist in the first place of making the tapping passages labyrinthine in shape, and in the second place of providing, as actuating members for the operation of automatically closing the slide valves, weighted levers which are so constructed that the slide valves become closed not only when the container or barrel is stood up on end or tilted in a vertical plane but also on rotation of the same about its longitudinal axis.

According to a particular form of construction of the invention the weighted lever takes the form of a pivoted lever which is so designed that it closes the shutting off member in any position of the container, except for the position of use for tapping, in which it might be possible to pour liquid into the container through the tapping outlet. The weighted two-armed lever is de-

signed to serve as the carrier of the shutting off member which governs the air and liquid passages, and which preferably takes the form of a straight movement slide valve, and presses this slide valve against its bearing surface, the pressure of contact being regulable by suitable means, such as for example by a screw.

The casing of the device is substantially in the form of a flat box, and is adapted to be screwed into a ring for attachment to one end of the container, and to be secured against removal by means of elements which are inaccessible from the outside. In order to obtain maximum rates of flow, the liquid outlet and air inlet passages are very considerably widened and expanded, are substantially of rectangular shape in cross-section, and are so disposed that the liquid passage assumes a position as low down as possible in the container and the air passage as high up as possible, for the purpose, on the one hand, of preventing the formation of an air-lock in the air passage, and, on the other hand, of enabling the container to be as far as possible completely emptied. At the same time provision is made, in accordance with the invention, for enabling the bearing surface for the slide valve to be located as close as possible to the bottom of the container.

The cock plug is so constructed that on its rotation into the open position the outlet passage for the liquid contents of the container is opened earlier than the inlet passage for the air, the result being that the liquid in the container produces a partial vacuum by which, when the air passage is opened a short time afterwards, air is drawn into the container through this latter passage. At the same time the air inlet passage and the liquid outlet passage are inter-connected in the cock plug by a communal space.

For transport, the outside fittings, that is to say the head of the cock plug and the end portion of the casing, can be closed over by means of a sealing cap which prevents removal of the handle of the tapping cock, and provides a particularly favorable possibility of sealing the device as a protection against tampering.

A form of construction embodying the invention is shown, by way of example, in the accompanying drawings, in which:

Fig. 1 is a section of a tapping and refill-controlling device in accordance with the invention, in section taken on the line *c—d* of Fig. 2.

Fig. 2 is a section on the line *a—b* of Fig. 1.

Fig. 3 is a side elevation of the device.

55

Fig. 4 shows the device in front elevation with the cock plug removed.

Fig. 5 shows the device in a tilted position.

Fig. 6 shows the device in a position assumed 5 when the container is revolved about its longitudinal axis so that the spout is disposed at the side.

Fig. 7 shows the locking elements, the cock plug, and the casing, in rear end elevation, the 10 locking elements being shown in the locking position.

Fig. 8 shows the same view as Fig. 7, but with 15 the locking elements moved to their inward position to unlock the plug to permit its removal from its casing.

Referring to the drawings, the casing or housing 4 into which the cock plug 5 is removably inserted, is provided top and bottom with a laterally extending socketed portion 50^a and 51^a, respectively, having, inside the container, a communal bearing surface 52 for a slide valve 53. The passages 70, 71 in the sockets 50^a and 51^a are multiple-curved, as can be seen from Fig. 1. 20

The portion of the passage nearest the cock 25 plug is in each case cut off from direct communication with the outer portion terminating at the respective apertures in the slide valve bearing face by a curved partition or cowl 72 and 73, respectively, which makes it impossible for a flexible implement, such as a piece of wire, to be introduced through the apertures in the cock plug 5 up to the apertures 70^a and 71^a in the communal slide valve bearing face to interfere with the functioning of the slide valve 53. The passages 70 30 and 71 are widened out to the greatest possible extent, and are made as large as possible in cross-section, so as to put as little check as possible on the flow of media therethrough. At 70^b, 71^b these passages are provided with special chambers 35 which permit the remaining cross-section to be kept as shallow as possible, so that the device can be fitted very close to the cylindrical jacket 2 of the container, when the latter is a barrel, and also as low down as possible, as indicated in the 40 drawings.

The slide valve 53 is furnished with an aperture 54, and is pressed against its bearing surface by 45 the two-armed lever 62 which is pivoted at 59 on an extension or lug 60 on the casing 4 of the device. The lever 62 is provided at 75 with a wrist-pin by means of which there is articulated to this lever a weight 76 which is pivoted relatively to but in the same plane as this lever 62. The slide valve is connected to the end of the 50 lever by means of an adjustable screw 82 which at the same time serves for the regulation of the contacting pressure between the slide valve and its bearing face.

The cock plug 5 fitted in the casing 4 is provided with apertures 38 and 39 which are interconnected by a communal space 84, and of which, when the plug is in the open position as shown in Figs. 2 and 3, the former communicates with the passage 70 in the socket 50^a and the latter 60 with the passage 71 in the socket 51^a, so that liquid can flow out of the container through the passage 71 and aperture 39, past the rib 46, and over the spout 4^a, while at the same time air 65 enters the container through the aperture 38 and the passage 70 in the socket 50^a. Since in 70 these circumstances the device, and more particularly the slide valve 53, is disposed in a vertical plane, the weight 76, acting through the intermediary of the lever 62, retains the slide valve 53

in the position shown in Figs. 1 to 3, in which the apertures 70^a and 71^a in which the passages 70 and 71 terminate, respectively, are disclosed. The cock plug 5 serves solely for the closing and opening of the tapping ports. The refilling passage, 5 on the other hand, is bounded by the inside wall of the cock casing 4 when the plug 5 is removed from the casing. However, the removing of the plug can not be effected until the cylinder lock 6 provided in the cock plug 5 has been unlocked 10 by means of a fitting push-key. The central pin 23, which is slotted as at 23^b for the key, is provided with an extension 23^a secured to a disc 33 which controls the movement of segments 35 adapted to engage behind the rear end surface 15 of the casing 4, in such a manner that rotation of the disc 33 in the one direction swings the segments into position behind the rear end surface of the casing, while rotation of this disc in the other direction moves these segments from the 20 locking position shown in Figs. 3 and 7 inwardly into a position in which they clear the cylindrical opening of casing 4 so that the cock plug 5 can be removed bodily from the casing 4, after which liquid can be poured into the container through 25 the opening in the casing normally destined for the reception of the cock plug. This pivotal movement of the parts shown in rear elevation in Figs. 7 and 8, and more particularly of the segments 35, is rendered possible by virtue of the fact 30 that on rotation of the pin 23^a the disc 33 is also rotated. Since the segments 35 are on the one hand articulated by means of pins 36 to the rear end surface of the cock plug 5 and on the other hand are provided with studs 34 which engage 35 appropriately curved slots 33^a in the disc 33, rotation of the disc 33, shown in locking position in Fig. 7, in a clockwise direction will cause the segments to be swung inwardly, the end position 40 of this movement in which they clear casing 4 being shown in Fig. 8.

Since however only the owner of the container, and not any dealer or other person holding it on loan, is in possession of the key to the lock 45 which governs the removal of the cock plug no one else but the owner of the container is in a position to refill it. The attempt could nevertheless be made by unauthorized persons to refill the container with liquid of a different nature or of a different quality from that with which it was originally filled. For this purpose the barrel shown in the drawings could be tilted up on end (Fig. 5) or rotated (Fig. 6) about its axis (for example by being rolled on the 50 cylindrical jacket 2), in which latter case the device according to the invention (Fig. 1) is likewise turned until the cock plug or for example the spout 4^a is at a higher level than the top of the upper aperture in the slide valve 53. However, as soon as the device goes beyond the position in which the bearing surface for the slide valve is horizontal in the course of such rotary movement, the weight 76 drops back from the 55 position shown in Fig. 3 to that shown in Fig. 6, 65 with the result that, through the intermediary of the two-armed lever 62, the slide valve 53 closes over the ports in the bearing face for the passages 70, 71, and thereby renders it impossible for liquid to be introduced into the barrel 70 or other container through these latter passages. The same naturally occurs when the container, and with it the device according to the invention, is tilted backwards from the horizontal position towards the upright position, as indicated by the 75

arrow p_5 in Fig. 5 of the drawings. At these changes of position of the container the lever 62 moves about its pivot, in the direction indicated by the arrow p_6 in Fig. 5, only until the abutment 80 on this lever comes into contact with the upper part of the casing 4.

The introduction of a wire or other similar implement into the passages 70 and 71 is effectually guarded against by the provision of the intercepting partitions 72 and 73, since these latter, being curved, tend to turn over the end of the wire or other implement and eventually twist this latter up into a coil if the attempt be made to thrust it further in. It is consequently quite impossible to pass a piece of wire or the like up the passages 70 and 71 as far as the point at which these passages open into the interior of the container.

The relatively small diameter of the opening in the cock casing is liable to impede the cleaning out of the container to which the device according to the invention is fitted. When this device is welded into one of the ends of the container, as in the case of a barrel, the troublesome and expensive operation of opening the weld becomes necessary before readjustment of any of the moving parts of the device can be effected or repairs done to the slide valve. This necessity is avoided by the following arrangement.

30 The casing of the device is united to the wall of the container by means of a screw connection which is indirectly protected by the cock plug itself, the arrangement being, for example, to provide a front flange 86 of the casing 4 of suitably large diameter, with external screw threading, so that this part can be screwed into a suitable ring 87 in the end wall 1 of the container, this screw joint being locked by means for instance of a grub screw 88 extending obliquely 40 through the casing 4 and adapted to be screwed into the ring 87 thus preventing relative rotation between this ring and the casing and slackening of the described screw joint between these parts. Between the ring 87 and the rim flange 45 86 there is fitted a packing ring 92. On the spout 4^a there are provided ribs 90, 90 to which if desired there can be fitted an additional lip member 91 to facilitate the dispensing of the contents of the container and to catch drops.

50 The apertures in the bearing face for the slide valve to work against in the interior of the container are disposed as far apart as possible, so as to enable the outlet aperture for the liquid contents of the container to be disposed close 55 to the wall of the container, while the aperture for the admission of air is disposed as high up as possible. The registering apertures or ports in the cock plug, or the edges of these apertures, are so disposed relatively to each other that when 60 the cock plug is rotated into the open position the outflow passage becomes opened in advance of the air inlet passage, for reasons explained above.

In order to make the slide member 62 light in 65 weight this part can be made by pressure molding or die casting from oil-proof artificial resin, for instance from "Bakelite".

When in position in the casing of the device, the cock plug prevents access to the grub screw passing through the casing into the ring attached to the wall of the container.

I claim:

1. A tapping and refill-controlling device for attachment to a container of dispensable liquid, comprising in combination a stopcock casing

with a through central bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the said device in space.

2. A tapping and refill-controlling device for attachment to a container of dispensable liquid, comprising in combination a stop-cock casing with a through central bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, the said passages being curved in their length, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the said device in space.

3. A tapping and refill-controlling device for attachment to a container of dispensable liquid, comprising in combination a stop-cock casing having a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, the said passages being each composed of two limbs of different curvature having a wall in common where they are adjacent each other, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the said device in space.

4. A tapping and refill-controlling device for attachment to a container of dispensable liquid,

comprising in combination a stop-cock casing having a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, the said passages being each composed of two limbs of curved shape having a wall in common where they are adjacent each other, and the said wall being shaped like a cowl over the end of the passage nearest the said plug, for the purpose of preventing the introduction of a tampering implement into the said passages up to the said ports in the said bearing face, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the entire device in space.

5. A tapping and refill-controlling device for attachment to a container of dispensable liquid, comprising in combination a stop-cock casing with a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the entire device in space, the said weight-controlled means comprising a two-armed lever fulcrumed on the said casing and articulated with one arm to the said slide member, and a weight articulated to the other arm for pivotal movement relatively to and in the same plane as the said lever.

6. A tapping and refill-controlling device for attachment to a container of dispensable liquid, comprising in combination a stop-cock casing having a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face,

an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the said device in space, the said weight-controlled means comprising a two-armed lever fulcrumed on the said casing and articulated to the said slide member with one of its arms, and a weight articulated to the other arm for pivotal movement relatively to and in the same plane as the said lever, the said weight-controlled means being adapted to keep the said slide member constantly pressed against the said bearing face.

7. A tapping and refill-controlling device for attachment to a container of dispensable liquid, comprising in combination a stop-cock casing having a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the entire device in space, the said weight-controlled means comprising a two-armed lever fulcrumed on the said casing and adapted to keep the said slide member constantly pressed against the said bearing face and articulated with one arm to the said slide member, and a weight articulated to the other arm for pivotal movement relatively to and in the same plane as the said lever; the said device further comprising a set-screw associated with the said lever and bearing against the said slide member for adjusting the pressure between the contacting surfaces on the said member on the one hand and its bearing or working surface on the other hand.

8. A tapping and refill-controlling device for attachment to a container of dispensable liquid, comprising in combination a stop-cock casing with a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, an air inlet and a liquid outlet port in the said plug adapted to register with the said ports in the bore of the casing, a hollow space in the said plug adapted to establish inter-communication between the air inlet port and the liquid outlet port in the said plug, an apertured slide

member adapted to work against the said bearing face and to close and open the said ports in said face in its two operative end positions, respectively, and weight-operated means for actuating the said slide member in dependence on the position of the said device in space.

9. A tapping and refill-controlling device for attachment to a container of dispensable liquid, comprising in combination a stop-cock casing having a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, an air inlet and a liquid outlet port in the said plug adapted to register with the said ports in the bore of the casing, a hollow space in the said plug adapted to establish inter-communication between the air inlet port and the liquid outlet port in the said plug, the said ports in the plug being so disposed relatively to each other that at the opening movement of the said plug the liquid outlet ports in the said plug and bore wall are caused to register in advance of the corresponding air inlet ports, an opertured slide member adapted to work against the said bearing face and to close and open the said ports in said face in its two operative end positions, respectively, and weight-op-

erated means for actuating the said slide member in dependence on the position of the said device in space.

10. A tapping and refill-controlling device for attachment to a container of dispensable liquid, comprising in combination a stop-cock casing having a central through bore, a cock plug rotatably fitted in the said bore, key-controlled means for locking the said plug against axial movement in the said casing and for releasing the same for removal from the casing to clear the said bore for the purpose of refilling the container, a plane bearing face at the side of the said casing, ports in the wall of the said bore, ports in the said bearing face, an air inlet and a liquid outlet passage in the said casing leading severally from one of the said ports in the wall of the bore to the corresponding one of the said ports in the bearing face, an air inlet and a liquid outlet port in the said plug adapted to register with the said ports in the bore of the casing, an apertured slide member adapted to work against the said bearing face and to close and open the said ports in said face in its two operative end positions, respectively, and weight-operated means for actuating the said slide member in dependence on the position of the said device in space; and further comprising screw threading on the periphery of the said casing, a ring member screwed on the said threading and adapted to be attached to the said container, a tapped hole in the said ring member for the reception of a locking grub screw, and a registering socket in the said casing terminating at a point normally covered over by the said plug.

CHRISTOPH KARAGEORGIEFF.
